UNITED STATES PATENT OFFICE

CHARLES HAZOR SMITH, OF CHICAGO, ILLINOIS.

GARMENT-FASTENING.

SPECIFICATION forming part of Letters Patent No. 665,479, dated January 8, 1901.

Application filed December 18, 1899. Serial No. 740,675. (No model.)

To all whom it may concern:

Be it known that I, CHARLES HAZOR SMITH, a citizen of the United States of America, residing at Chicago, in the county of Cook and 5 State of Illinois, have invented certain new and useful Improvements in Garment-Fastenings, of which the following is a specification.

My invention relates to certain improvements in a holding device intended for use 10 by tailors, dressmakers, and other fitters of clothing, designed to temporarily secure in place the pieces of a garment as the same are fitted or adjusted to the wearer in the course of their manufacture. This has ordinarily 15 been done by the use of common pins passed through both pieces of fabric, which makes the goods awkward to handle, is insecure, and interferes with the sewing up at the points of union.

20 The object of the invention is to combine two holding devices by means of an adjustable connection, so that said devices may be secured, respectively, to the adjoining pieces of the garment, adjusted to the proper position, and securely held there until the same is completed.

To such end the invention consists in certain novel characteristics contained in the preferred form of the invention shown and 25 described herein, said characteristics being definitely pointed out in the claim.

In the drawings, Figure 1 is a plan view of the complete device. Fig. 2 is a section in line 2 of Fig. 1. Fig. 3 is a section in line 35 3 of Fig. 1, and Fig. 4 an end elevation of the right-hand portion of Fig. 1 looking in the direction of the arrow 4 of said figure.

The preferred device herein shown contains two ordinary safety-pins A B. A plate 40 C is bent about one end of the safety-pin A and secured by means of an eye c to a chain D, preferably provided at its free end with a ring d. About one side of the safety-pin B is bent a plate E, one end of which bears two 45 ears e, projecting in the same direction and embracing the other end e' of the plate, which is preferably formed so as to act as a spring pressing toward the ends of the ears. Between the ears is pivoted a bent lever F, having 50 a handle f, extending alongside of the plate E, and a short end f', extending toward the end e' of said plate. Said lever is shown

as pivoted by means of two laterally-extending tongues f² f³.

The chain D is passed between the lever F 55 and the spring end e' of the plate E. As before stated, the spring e' presses toward the ends of the ears, and therefore toward the short end of the lever. Said short end is so arranged with reference to the handle f 60 that when the latter strikes the plate E, as seen in Fig. 3, the short end of the lever will have passed beneath the pivotal axis, so that the tension of the spring tends to hold the lever in the position shown. This furnishes 65 a secure grip upon the chain and at the same time provides easy means of adjustment.

In the use of the device the garments are placed upon the person who is to wear them, the pins A B secured to the contiguous portions of the garment which need adjustment, and said portions then drawn up to a perfect 70 fit and secured in position by adjusting the chain D in the clasp-plate E. The garment is then taken off and sewed up at the convenience of the tailor or dressmaker. It is 75 impossible for the different parts to get out of place, and at the same time the pins may be located so far apart as to not interfere in the least with the sewing up of the garment 80 between them.

While the fitting of garments, as described above, is the use to which I have thus far applied my invention, and while its utility for that purpose is evident, it is equally evident 85 that it may be applied to other uses in which it is desirable to so connect any two parts that the space between them may be readily and conveniently varied. It will be understood, therefore, that I do not intend to limit 90 the invention to the use hereinabove pointed out, but that I desire to claim it no matter what its function may be. As shown in the drawings and hereinbefore described, the device has the details of construction which I 95 have embodied in it in reducing it to practical and operative form. It will be evident, however, to any mechanic that these details may be greatly varied, the essential requisite being that the safety-pins shall be joined by 100 a suitably-adjustable connecting element, so that the distance between the pins may be conveniently changed in the use of the device. For most purposes the chain will be

found most desirable, for the reason that it is flexible, easily fastened, and very durable; but evidently the chain may be replaced by a cord, tape, or wire or even by some device made up of parts adjustable with relation to each other. I desire, therefore, not to limit the invention to the combination of the exact elements shown in the drawings, but, on the contrary, to give it the scope indicated in the following claim.

I claim as new and desire to secure by Letters Patent—

The combination with the pins, A, B, of the plate, E, secured about one of said pins, having its two ends extending in the same direction, one alongside of the other, one of said ends bearing the ears, e, and the other end extending in the form of a spring between

said ears, the angle-lever, F, pivoted between the ears, having one end extending alongside of the plate, E, and the other toward the same when the lever is in the closed position and a connecting device secured to the other pin and adapted to be engaged at a plurality of points between the short end of the lever, F, and the opposing spring end of the plate, E; substantially as described.

In witness whereof I have hereunto set my hand, at Chicago, in the county of Cook and State of Illinois, this 15th day of December, 1899.

CHARLES HAZOR SMITH.
